UNITED STATES PATENT OFFICE.

WILLIS W. CASE, JR., OF DENVER, COLORADO.

METALLURGICAL-FURNACE PART.

1,085,540.

Specification of Letters Patent. Patented Jan. 27, 1914.

Application filed September 22, 1912. Serial No. 791,128.

To all whom it may concern:

Be it known that I, WILLIS W. CASE, Jr., a citizen of the United States, residing in the city and county of Denver and State of Colorado, have invented certain new and useful Improvements in Metallurgical-Furnace Parts; and I do hereby declare the following to be a full, clear, and exact description of the invention, such as will enable others skilled in the art to which it appertains to make and use the same.

This invention relates to metallurgical furnace parts, and more particularly to a crucible and its mounting in said furnace, whereby the same may be used as a crucible proper or converted into a retort.

In the present application I do not claim the specific form of furnace with its lining, comprising a plurality of closely spaced refractory projections engaging the walls of the crucible, which feature is claimed in my Patent #1,066,995, patented July 8, 1913, although for the purpose of a complete disclosure reference is had to the accompanying drawings, illustrating a practical embodiment of my invention as applied to a tilting furnace, and the particular features of novelty of the said invention will be pointed out more precisely in the 30 claims.

In the drawings forming a part of this application like numerals designate the same parts in the several views, in which— Figure 1 is a central vertical sectional view through a tilting furnace embracing my invention. Fig. 2 is a top plan view of the crucible lid. Fig. 3 is a side elevation of said lid looking in the direction of the arrow in Fig. 2. Fig. 4 is a fragmentary vertical sectional view on the line 4—4 of Fig. 1 looking in the direction of the arrow. Fig. 5 is a fragmentary sectional view showing a slightly modified form of the spout of the crucible associated with the lining 45 of the discharge trough from the furnace, and Fig. 6 is a similar view to Fig. 3 showing a modified form of crucible lid omitting the central aperture.

While the following parts do not constitute essential features of the present invention, they may be briefly referred to as comprising an iron sheathing 1 incasing the furnace walls 2 the furnace being provided with a lower chamber 3, and an upper chamber 4, said upper chamber being lined with blocks 5, provided on their inner faces with

a plurality of closely spaced heating projections adapted to engage a crucible contained therein and supported by the legs 6 of a pedestal mounted in said lower chamber 3. The upper chamber 4 and the lining blocks 5 are curved as shown to comply with the upwardly curving contour of the crucible hereinafter referred to.

7 designates a suitable support, secured to the furnace lining, on which is mounted a vertical sleeve 8, containing a vertically reciprocating spindle 9, said spindle carrying a rotary support 10. The rotary support 10 is provided with an operating handle 11 and an arm 12, which arm is connected with an iron band 13, surrounding and securely attached to the furnace cover 14, which is provided with a central opening 15, and which cover may be stayed from said support 10 by suitable stay rods 16.

17 is a plug for closing an opening, leading from the bottom chamber 3 to withdraw any molten metal should the crucible from any cause break, and 18 is a pawl controlled lever for reciprocating the spindle 9, whereby the latter and the cover 14, may be lifted off of the furnace and revolved laterally from above same by the handle 11.

19 is a discharge spout formed on the top edge of the furnace wall, and is substantially semi-cylindrical in cross-section.

In the present application I do not claim any features broadly thus far described, as they have been claimed in my former patent referred to, covering the particular type of tilting furnace mentioned.

In my present invention, I employ and claim a particular type of crucible, which may be utilized with a furnace, as a crucible ⁹⁵ *per se*, and which also may be converted into a retort, a very important feature to those engaged in metallurgical pursuits.

The trough 19, broadly referred to, is provided with a lining 20 of any suitable material, but preferably formed of plumbago, and is substantially semi-cylindrical to fit said discharge trough, the inner edge of said lining 20 being provided with an internal flange 21. The crucible 22 is formed with a short spout 23, of substantially semi-cylindrical contour, adapted to snugly rest on and be surrounded by the internal flange 21 of the lining 20. The short spout 23 is not in the nature of a lip discharging at the top edge of the crucible but the lower surface of the spout extends at right angles

to the major axis of the crucible, and is cut away in a vertical plane, as at 24, forming an open ended spout of substantially semi-cylindrical construction, the base or pouring position of which is located at a substantial distance beneath the top edge of the crucible, and outwardly beyond the internal flange 21. By this construction, should more material be charged into the crucible than the crucible will contain, the bottom of the spout 23, being located a considerable distance below the top edge of the crucible proper, the molten metal will flow out through the trough before it can reach the top edge of the crucible, which will prevent the molten metal from slopping over the top edge of the crucible and between it and the furnace lining, thereby saving the checkered furnace lining from destruction. Also should such a condition arise, and the metal begin to flow out of the spout into the trough 19, the internal flange 21 will prevent the metal from slopping backwardly through the trough between the same and the crucible spout, so that under no conditions can the molten metal come in contact with the furnace lining from any such causes.

In converting the crucible into a retort I provide a cover 25 of peculiar formation as shown in Figs. 1 to 4, and which is substantially circular for the greater portion of its area, merging into an extension or lip 26 which terminates in a straight edge 27, forming a cover for the spout of the crucible, while the circular portion forms a lid for the crucible proper, the underneath face of the lid or cover 25 being provided with an annular recess 28, forming a circular projection 29, the said recess 28 providing a seat or ledge 40 engaging the top edge of the crucible, and the said circular projection 29 snugly fitting the interior walls of the crucible around the major portion of its upper edge. This lid or cover is also provided on its upper face 45 with a central boss 30, which curves downwardly and merges into the upper face of the lid. The lid and boss may also be provided with a small central bore 31, said boss being adapted to project a short distance 50 within the opening 15 of the furnace cover. The lid may also be provided if desired with a raised reinforcing portion 32, projecting from the body of the lid along the extension 26, as shown more clearly in Fig. 2. The 55 underneath face of the furnace cover 14 is recessed as at 33 providing a flanged base 34 for supporting the cover on the furnace, the recess being of such a depth and of such a diameter that it forms, with the outer surface 60 of the crucible lid, a passageway for carrying off the products of combustion, which pass upwardly and through the furnace, between said checker-work of heater projections, and outwardly through the 65 opening 15 in the cover, while the fumes

from the retort may pass outwardly through the open ended spout 23, and also through the aperture 31, where the lid is provided with such aperture. In Fig. 6 there is shown, however, a lid 25^a similar to the lid 25, with the exception that the same is not provided with the aperture 31, and where such a lid is employed the discharge of fumes from the crucible-retort would be through the open ended spout 23.

In Fig. 5 there is shown a slight modification wherein not only is the lining 20 provided with an internal flange 21, but the spout 23^a is also provided on its outer end with a depending flange 21^a, forming a more compact joinder between the spout and plumbago lining, to prevent back slopping, as previously mentioned.

From the foregoing detailed description it is not believed to be necessary to further describe the operation of the invention, for as before explained, no claim is made to the furnace proper or to the tilting features thereof.

Having thus described my invention, what I claim is:

1. As a metallurgical furnace part, a crucible having an open upper end provided with a short spout of substantially semi-cylindrical construction and cut away at right angles at its outer end, forming a discharge surface substantially below the top edge of the crucible, the outer surface of said spout being provided with an external peripheral flange, surrounding the discharge end of said spout.

2. As a metallurgical furnace part a convertible crucible-retort, comprising a crucible proper, open at its upper end and provided with an open-ended short spout disposed at right angles to the vertical axis of said crucible, said spout being substantially semi-circular in cross-section, and a lid provided on its underneath face with an annular recess forming a ledge adapted to seat snugly on the upper edge of said crucible, said cover being provided with an extending lip or otherwise adapted to cover said spout, and said lid being also provided on its upper face with a central boss, curving downwardly to meet the upper surface of the lid.

3. A crucible for metallurgical furnaces having an open upper end provided with a short spout, substantially semi-circular in cross-section, said spout being open-ended and disposed at right angles to the major axis of said crucible, and a substantially semi-circular lining, forming a pouring trough adapted to be mounted on the furnace and provided at its inner end with an inturned flange adapted to seat the outer surface of said spout.

4. A crucible for metallurgical furnaces open at its upper end and having a short

curved spout projecting horizontally therefrom, providing a discharge surface substantially below the top edge of the crucible, the outer surface of said spout being provided with an external peripheral flange, and a curved lining forming a pouring trough, adapted to be mounted on said furnace and provided at its inner end with an inturned flange adapted to seat below said 10 spout on the inside of its external flange.

5. The combination with a metallurgical furnace of a crucible mounted therein and provided at its upper open end with a horizontally disposed curved spout open at its 15 top and outer end, providing a discharge surface substantially below the top edges of the crucible, a lid for said crucible having an annular recess on its underneath face

providing a ledge adapted to snugly seat on the top edge of said crucible, said lid being provided with an extending lip or otherwise adapted to cover the upper portion of said spout, a central boss formed on the upper face of said lid, and a removable cover for said furnace provided with a central aperture and a recess on its lower face, for forming a passageway between said furnace cover and crucible lid to conduct the products of combustion through said central opening.

In testimony whereof I affix my signature, in presence of two witnesses:
